UNITED STATES PATENT OFFICE

THOMAS N. JOHNSON, OF ROME, NEW YORK

ENVELOPE OPENER

Application filed May 11, 1931. Serial No. 536,570.

The present invention relates to an envelope opener and has for its prime object to provide an apparatus whereby envelopes may be opened in an easy and expeditious manner by cutting off one edge thereof.

Another very important object of the invention resides in the provision of an apparatus of this nature which is exceedingly simple in construction, inexpensive to manufacture, strong and durable, easy to manipulate, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the apparatus embodying the features of my invention.

Figure 2 is a top plan view thereof.

Figure 3 is a sectional view taken substantially on the line 3—3 of Figure 2.

Figure 4 is an end view of the apparatus.

Figure 5 is a sectional view taken substantially on the line 5—5 of Figure 3.

Figure 6 is a sectional view taken substantially on the line 6—6 of Figure 2, and

Figure 7 is a fragmentary perspective view of one end of the tray.

Referring to the drawings in detail it will be seen that the numeral 5 denotes a block on one side of which is secured a tray comprising a bottom 6, a side 7 rising therefrom, and ends 8 rising therefrom. One end 8 is provided in its upper edge with a notch 9. The side 7 may be provided with openings 10.

The bottom 6 is secured on the block 5 at one side thereof so that the side wall 7 is disposed in spaced relation to said side. Screws, pins or the like 12 are engaged in said side of the block to extend a slight distance in the tray and have thereon a plate 14, the upper edge of which is flush with the upper edge of

the block 5 and one end of which is curved outwardly from the block as at 15. Another plate 16 is on the pins or screws and has an end 17 turned inwardly opposite from the end 15 to engage the plate 14, thus holding the plates 14 and 16 normally spaced.

A knife or blade 18 has one end pivoted on one of the pins or screws adjacent offset end 15 between the plates 14 and 16, the notch 9 being provided to accommodate the handle 19 of the blade or knife. Plate 16 has its intermediate portion bellied inwardly as is clearly illustrated in Figure 5.

An envelope is placed on top of the block 5 with the edge desired to be opened extending over the upper edges of the plates 14 and 16 and the blade 18 is swung downwardly thus severing off this edge of the envelope and the cooperation of the offset ends 15 and 17 of the plates 14 and 16 insure a clear cut of the envelope so that the same is severed in an expeditious manner.

It is thought that the construction, utility and operation of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In an apparatus of the class described, a block, pins projecting from a side of the block, a plate on the pins, a second plate on the pins, and a blade pivoted on one of the pins between the plates, the first mentioned plate having an offset end bearing against the pivoted end of the blade, the second mentioned plate having an offset end remote from said end of the first mentioned plate to en-

gage the first mentioned plate and hold the second mentioned plate in spaced relation to the first mentioned plate.

2. In an apparatus of the class described, a block, pins projecting from a side of the block, a plate on the pins, a second plate on the pins, and a blade pivoted on one of the pins between the plates, the first mentioned plate having an offset end bearing against the pivoted end of the blade, the second mentioned plate having an offset end remote from said end of the first mentioned plate to engage the first mentioned plate and hold the second mentioned plate in spaced relation to the first mentioned plate, the second mentioned plate having its intermediate portion bellied inwardly toward the first mentioned plate by the pressure contact of the offset end portion of the second plate against the first mentioned plate.

In testimony whereof I affix my signature.
THOMAS N. JOHNSON.
